UNITED STATES PATENT OFFICE

JULIUS C. PETERSON, OF CHICAGO, ILLINOIS

INTERNAL COMBUSTION ENGINE

Application filed August 31, 1928. Serial No. 303,223.

My invention relates to internal combustion engines of the four stroke cycle type and particularly to those engines in which a fuel mixture, formed outside the cylinder, enters the cylinder through a valve and in which the products of combustion leave the cylinder through another valve. My invention relates particularly to the valves, to the valve actuating mechanism, and to a cylinder block and cylinder head adapted to the use of the valves. The principal objects of my invention are: first, to provide a valve which offers very little resistance to the flow of vapor or gas through it; second, to provide a valve which, when used as an exhaust valve, requires less force for its opening than is required for the opening of the usual poppet valve; third, to provide a valve which, when used as an exhaust valve, does not overheat; fourth, to provide a valve and compression chamber such that the greater part of the volume of the compression chamber is contained within the cylinder proper; fifth, to provide a valve actuating mechanism that is positive in action as to the closing of the valve; sixth, to provide a valve which automatically opens farther at higher engine speeds than it opens at lower engine speeds; seventh, to provide a valve which remains open for a relatively longer period at higher engine speeds than at lower engine speeds; and eighth, to provide adequate lubrication for the bearings of the valve.

Another object of my invention is to provide such positioning of the valves as will permit of their being of maximum diameter for an engine having cylinders of a given diameter and a crankshaft of a given length.

Further objects of my invention are to accomplish the foregoing objects in such a way that no difficulties of manufacture shall be encountered, that the mechanism shall be durable, that it shall be easy of adjustment, and that it shall require a minimum of care and attention to keep it at maximum efficiency.

Having stated in a general way the principal features of my invention and the advantages to be obtained from its use, I will now describe the preferred form and how it operates.

My invention is particularly applicable to engines of the type in most common use, that is, with a water cooling system and vertical cylinders. However, it is adaptable to engines having other cooling systems, such as air cooling, and to engines having inclined cylinders or with cylinders arranged radially. The limitation of my description to a single type of engine is not to be understood as limiting the scope of my invention.

The drawings are in the main illustrative, and other forms, coming within the scope of my invention, are practical and I do not limit my invention to what is shown in the drawings.

Figure 1 is a vertical section through the engine on a plane containing the longitudinal axes of the cylinder and of the exhaust valve, the plane being normal to the axes of the cam shaft and crankshaft, the piston and connecting rod not being in section; the piston ascending on the exhaust stroke, the exhaust valve being open at its maximum and the intake valve being closed, the various parts being in the positions they take when the engine is running at its highest speed. Figure 2 is a top view of part of the cylinder head, the portion at the right being cut away to show a horizontal section on the plane 2 2 of Figure 1. Figure 3 is a top view of part of the cylinder block with the cylinder head removed, the portion near the center being cut away to show a horizontal section on the plane 3 3 of Figure 1, and the portion at the right being cut away to show a horizontal section on the plane 3' 3' of Figure 1, the valves not being shown. Figure 4 is a side view of part of the cam shaft. Figure 5 is a top view of the upper end of the valve stem. Figure 6 is a top view of the cupped washer which closes the upper part of the interior of the valve piston.

The cylinder head is substantially in the form of a rectangular block except for the reinforcement 1, which surrounds the openings of the exhaust passages 2 and the intake passages 3. The walls 4 of the exhaust passages and the walls 5 of the intake passages, are formed integral with the rest of the cyl-

inder head, as are the walls 6 of the wells in which the spark plugs 7 are positioned. Threaded holes 8 are formed in the bottoms of the spark plug wells, to receive the correspondingly threaded portions of the spark plugs.

The lower surface of the cylinder head is a plane, and the lower ends of the spark plugs lie in, or substantially in, this plane, so that 10 when the head 9 of the piston 10 ascends to its highest point on the exhaust stroke, the clearance between the piston head and the cylinder head may be a minimum without any chance for the spark plug to be touched by the 15 piston head.

Between adjacent gas passages, and also near the ends of the cylinder head, are holes 11 for bolts to hold the cylinder head in position. The holes 11 accurately register with 20 the threaded holes 12 in the top of the cylinder block, the threaded holes 12 receiving the threaded ends of the bolts which hold the cylinder head in position. Other holes 13, positioned in the ends of the cylinder head 25 and along the side of the head opposite that containing the holes 11, are provided to receive other bolts for holding the cylinder head in position. The holes 13 accurately register with the threaded holes 14 in the top of the 30 cylinder block, the threaded holes 14 receiving the threaded ends of bolts which hold the cylinder head in position. The hole 15 is an outlet for water of the cooling system, the threaded holes 16 being for bolts to hold the 35 water manifold (not shown) in position. Holes 17 in the bottom of the cylinder head register with corresponding holes in the top of the cylinder block, providing passages for the cooling water from the cylinder block to 40 the cylinder head.

This form of cylinder head is very simple to cast and to handle during machine operations, which are very few, keeping down the cost of manufacture. The gas passages are 45 short and unobstructed. The spark plug wells act as reinforcements to strengthen the head to withstand the pressure in the cylinders.

The upper part of the cylinder block is also 50 substantially in the form of a rectangular block, and the upper surface is a plane of the same over all dimensions as the lower surface of the cylinder head. The holes 18 register with corresponding holes in the bottom of the 55 cylinder head, providing passages for the cooling water to flow from the cylinder block to the cylinder head. The usual gasket 19 is used to make a gas tight and water tight joint between the cylinder block and the cylinder 60 head.

The bore of the cylinders, formed by the cylinder walls 20, is of uniform diameter throughout its length, permitting the piston 10 to ascend to within mechanical clearance 65 distance of the cylinder head, on the exhaust

stroke, when the piston is of the type described in my application for Letters Patent, to which the Patent Office has given the Serial Number 288,150, series of 1925, and which was filed June 25, 1928.

A valve recess 21, connected with the bore of the cylinder, is formed in the top of the cylinder block. The depth of the recess is uniform and such that when the valve is open to its maximum, the top of the valve head 22 will be substantially in the same plane as the bottom of the recess. The walls of the valve recess are formed to give smooth surfaces which will cause very little interference with the exhaust gas leaving the cylinder, and which will cause part of the fuel mixture entering the cylinder to flow around the exhaust valve piston, helping to cool it, and which will cause sufficient turbulence of the fuel mixture to insure the residual burned gas being thoroughly mixed with it, so that combustion on the power stroke will be uniform. That part of the fuel mixture which flows around the exhaust valve piston, receives therefrom a certain amount of heat, 90 which helps to vaporize any unvaporized fuel in the fuel mixture.

When the valves are closed, the valve pistons occupy a large part of the volume of the recess, and only the remaining part of the volume contains residual burned gas at the completion of the exhaust stroke. This remaining volume may be as small as three percent (3%) of the total volume of the cylinder. The bore of the cylinder is of uniform diameter throughout its length, and the closure of the upper end of the cylinder is parallel to the piston head when the latter is at the end of the exhaust stroke. This construction, in connection with a piston, such as referred to above, in which the head of the piston may be constructed with a two percent (2%) clearance volume, permits ninety-five percent (95%) of the products of combustion to be expelled from the cylinder on the exhaust stroke.

A shallow circular depression 23 is formed in the bottom of the recess 21, the diameter of the depression being slightly larger than the over all diameter of the exhaust valve head 22, and the depth of the depression being such that suitable clearance will be left between the bottom of the depression and the lower exterior surface of the valve head, when the valve is open at its maximum. Another similar depression 24 is formed in the recess 21 for the intake valve. Concentric with the depression 23, the cylindrical exhaust valve well 25 is formed in the cylinder block, the walls 26 of the well being an integral part of the cylinder block. The exhaust valve piston is positioned in this well, and intake valve piston is positioned in the similar intake valve well 27, which has the walls 28, also formed integral with the cyl- 125 130

inder block. The bottom of each valve well is closed by a removable screw plug 29, which is screwed into a threaded hole formed in the bottom of the well. In the center of the plug 29 is a cylindrical hole of such size as to form a sliding fit with the valve stem 30.

The exhaust valve well is surrounded by the water of the cooling system. The intake valve well is similarly surrounded by water except for a short distance where the well wall and the cylinder wall unite in order that the intake valve may be positioned as closely as possible to the cylinder. A slight reduction in the diameter of either one or both of the valves will permit the intake valve well to be positioned so that it may be entirely surrounded by water, when this is desired.

The positioning of the valve wells in pairs, each pair on a line diagonal to the plane containing the longitudinal axes of the cylinders, permits the valves to be of large diameter without interfering with the adequate cooling of the valve wells and with the distance between cylinder centers kept at a minimum.

25 The threaded hole 31 is provided for making a connection with the oiling system so that lubricating oil will be supplied to the exhaust valve well by the oil passage 32 and to the intake valve well by the oil passage 33. The outlet oil passage 34 provides for the escape of surplus oil from the exhaust valve well to the space containing the push rod 35. The outlet oil passage 36 performs the same function for the intake valve well. 35 The oil that passes through the outlet oil passages collects in the depression formed on top of the crankcase, where the bearings 37 of the push rods are formed, providing lubrication for these bearings. The oil leaves the depression through the hole 38 in the top of the crank case, lubricating the parts of the valve actuating mechanism which are positioned within the crank case. The cover 39 keeps the oil from splashing out and prevents dirt getting into the oil. An adequate supply of oil is thus provided for the entire system of valves and actuating mechanism.

40 The crank case is formed integral with the rest of the cylinder block, with the walls 40, the transoms 41 in which the shaft 42 is positioned, and the projecting blocks 43 in which the bearings for the cam shaft 44 are positioned. This construction provides a 45 casting which may be readily manufactured, and the machine work required on it is simple and not of large amount.

The exhaust valve proper consists of two main parts. One of these is the valve piston, 50 consisting of the circular valve head 22 which has the conical surface 45 adapted to fit the conical valve seat 46 formed in the cylinder head at the entrance to the exhaust passage 2, and the cylindrical skirt 47, which has piston ring grooves formed in its exterior sur-

face to accommodate the piston rings 48 of the usual form.

The exterior diameter of the valve piston skirt is slightly less than the smaller diameter of the conical valve seat, so that when the valve is closed, the pressure in the cylinder on the compression and power strokes will act on the lower surface of the valve head and tend to keep it closed. However, the effective area against which the pressure acts is relatively small, so that on the exhaust stroke, when the valve must be opened against the pressure in the cylinder, the pressure does not interfere with the opening of the valve.

The distance of the upper piston ring below the valve head is such that the ring will not quite reach the top of the valve well in which the piston has a sliding fit, with the necessary clearance allowance for expansion, 55 when the valve is closed. The piston rings, in connection with the oil supplied for lubricating the valve, form a gas tight seal between the valve piston skirt and the bore of the valve well.

The lower inner surface of the valve piston skirt has a female screw thread 49 to receive a corresponding male screw thread on the outer cylindrical surface of the retaining ring 50. The retaining ring has an inner cylindrical surface to form a sliding fit with the corresponding cylindrical surface of the head 51 of the valve stem 30, which is the other main part of the exhaust valve proper. The retaining ring has an annular groove 52, the bottom of the groove being substantially of semicircular cross section, and the inner wall of the groove being slightly inclined to form a substantially conical surface, making the groove somewhat wider 60 at the top than at the bottom. The lower portion of the valve stem head 51 is formed into an annular ring 53, adapted to enter the groove 52, with a variable clearance between the ring and groove, provided by the inclination of the inner wall of the groove.

The groove 52 and the ring 53, together with the oil which enters the groove from the supply in the bottom of the valve well, form a dashpot to absorb the momentum of the valve piston when the latter is about to reach the limit of its upward motion as the valve closes.

54 is a compression spring which has one end bearing against the valve stem head 51, and the other end bearing against the cupped washer 55, which is seated against the shoulder 56 formed on the inner surface of the valve piston skirt. As the valve piston is capable of a limited motion relative to the valve stem head, in the direction of the axis of the valve, the valve spring, which is at all times under compression, tends to move the valve piston upward relative to the valve stem head.

The cupped washer 55 fits closely against the shoulder 56, forming therewith, when supplied with oil from the supply in the valve well, an air tight seal. The notches 57, in the outer circumference of the cupped washer, permit the escape of air from the closed chamber thus formed in the upper end of the valve piston, when the rise in temperature of the air therein, due to the heating of the valve, causes the pressure in the chamber to reach a point where it is greater than the pressure of the valve spring. The holes 58 in the valve stem head permit the passage of air through them, so that the air pressure is always the same on both the top and bottom of the head and the movement of the valve stem is not affected by the air pressure in the chamber formed by the cupped washer, the valve piston skirt and retaining ring, and the upper surface of the oil in the bottom of the valve well. The chief function of the cupped washer is to make the volume of this chamber relatively small, so that the compression of the air contained therein will be relatively high for the short distance which the valve piston moves downward. The openings into the valve well of the oil inlet passage 32 and of the oil outlet passage 34, are just below the lower edge of the valve piston skirt when the valve is closed. As the valve opens and the valve piston descends, both openings are closed. When the valve is closed, then, since the oil outlet passage 34 is open to a chamber where the air pressure is that of the atmosphere, the level of the oil in the bottom of the valve well will be approximately even with the openings of the oil passages, and the pressure of the air in the chamber will be that of the atmosphere. When the valve is open to its maximum, the volume of the chamber available for containing air may be as small as one third the volume available when the valve is closed. The corresponding increase in air pressure not only absorbs the momentum of the valve piston, bringing it quietly to rest, but greatly assists the valve spring in starting the valve piston upward on the closing part of the valve cycle. This relieves the rest of the actuating mechanism from much of the hardest part of its work, that is, stopping the downward motion of the valve piston and starting its upward motion.

This feature of my invention makes it practical to use a much lighter valve spring than would otherwise be required. As the inertia of the air is very small compared to that of springs, the response is much quicker and the lag of the motion of the valve piston behind the motion of the valve stem, on the closing stroke, can be varied by varying the capacity of the air chamber, so that the valve timing at high speed will be just that required for the best results, at the same time that the valve timing for lower speeds also remains

correct. The rest of the actuating mechanism may also be made lighter, and as it does less work and therefore gets less wear, its durability is increased.

The retaining ring 50 permits the various parts contained in the valve piston to be easily assembled and holds them in their assembled relation, and besides forming part of a dashpot with the ring 53, cooperates with that ring to form the connection between the valve piston and valve stem, necessary to cause the valve to open when the valve stem descends.

The lower end of the valve stem has a male screw thread 59 adapted to fit a corresponding female screw thread on the interior of the upper end of the hollow push rod 35. The lock nut 60 prevents any change in the adjustment of the distance between the bottom 61 of the push rod and the lower surface of the annular rings 53, without loosening this nut. The valve stem and push rod are thus practically a single continuous rod so far as the operation of the valve is concerned. The lower end of the push rod is enlarged and has a sliding fit in the cylindrical bearing 37 in the top of the crank case. The push rod spring 62 is a compression spring, the lower end of which bears against the washer 63, which in turn bears against the shoulder 64 on the push rod. The upper end of the spring bears against the plate 65, which is held in fixed position by bolts (not shown) which press it down against the top of the cylindrical spring housing 66. The push rod spring is always under compression and causes the bottom 61 of the push rod to maintain constant contact with the end 67 of the cam lever 68. The other end of the cam lever is hinged to the crank case by the shaft 42. The cam roller 69 is positioned in a slot in the cam lever, and rotates on the hollow pin 70 which is seated in the sides of the slot in the cam lever. The downward pressure on the end 67 of the cam lever causes the cam roller 69 to maintain constant contact with the surface of the cam 71 which is formed on the cam shaft 44, revolving at half the speed of the crank shaft, through the means of gears or a chain, in the usual manner.

The cam lever for the intake valve is similar to the one for the exhaust valve except that it is longer so as to reach the bottom of the push rod 73 for the intake valve. The cam 74 for the intake valve will have less eccentricity than the cam 71 for the exhaust valve, due to this difference in length of the respective cam levers. Both cams, however, are circular for the greater part of their contour, with the centers of their circles lying in the axis of the cam shaft. The portions of the contours having reduced radii govern the opening and closing of the valves, while the circular portions maintain the valves in their closed positions. The cam shaft has the cylindri-

cal bearings 75, of slightly greater radius than the maximum radius of the cams.

The intake valve is similar in construction to the exhaust valve.

The other necessary parts of the engine, not particularly designated and whether shown in the drawings or not, are assumed to be present and may be of any usual construction.

10 In the operation of an engine equipped with my invention, the exhaust valve, from the time it closes at the end of an exhaust stroke until it opens again at the start of another exhaust stroke, is kept closed by the 15 high part of the exhaust cam being in contact with the cam roller, causing the cam lever, push rod and valve stem all to take their highest positions, with the push rod spring compressed to its maximum, and the 20 valve piston held in its highest position by the pressure of the valve spring, so that the conical surface on the valve head fits closely into the conical valve seat in the cylinder head. The upper part of the valve piston 25 occupies a part of the volume of the valve recess. The valve spring is more than strong enough to keep the valve closed during the intake stroke while the pressure in the cylinder is less than atmospheric pressure.

20 During the compression and power strokes the pressure in the cylinder presses equally on every point in the cylindrical surface of the valve piston exposed in the valve recess, so that there is no tendency for one side of 25 the valve piston to press against the bore of the valve well more than any other side. Nor is there any tendency to push the valve head out of the valve seat. The lower surface of 40 the valve head, between the outer surface of the valve piston skirt and a circle of the same diameter as the larger circumference of the valve seat, is the effective area acted on by the pressure of the contents of the cylinder, tending to press the valve head upward into 45 its seat. This area is about 30% of the effective area acted on by the pressure in the case of an ordinary poppet valve of equal diameter, so that the effective pressure is about 30% of that acting on an ordinary poppet 50 valve.

As the ordinary poppet valve used as an exhaust valve gets very hot, particularly if the engine is run continuously for a long period, and the pressure is high, there is a tendency for it to stick in its seat. This sticking, together with the fact that the pressure on the valve head must be overcome in order to open the valve, requires the use of considerable power to open the valve. It is, therefore, not practical to open the valve by spring pressure, as the spring would have to be too strong in order to insure opening. Consequently the valve must be opened by the cam and the spring must be relied upon to close the valve. This results in inaccurate closing

at high speeds, due to the inertia of the moving parts. In my invention the valve is opened by a spring, so that the closing is accomplished by the cam action and is therefore positive, no matter what the speed of the engine may be. The pressure on my valve being about 70% less than that on the ordinary poppet valve, permits the use of a spring for opening the valve, particularly since my valve does not stick in its seat.

The area of the valve piston exposed to the heat of the contents of the cylinder during the power stroke is approximately equal to the area of the valve head of an ordinary poppet valve of equal diameter. The latter has the valve seat and valve guide to carry off the heat, and the mass of the heated metal is probably somewhat greater than in my valve, which has a similar valve seat and the relatively great area of water cooled valve well to carry off the heat. Moreover, the average distance which the heat must travel to reach a cooling surface in the ordinary poppet valve is much greater than the average distance the heat must travel in my valve. During the power stroke, therefore, my valve will remain much cooler.

As the piston nears the lower end of the power stroke, the lower part of the exhaust valve cam comes into contact with the cam roller and the push rod spring causes the push rod and valve stem to start to descend. The dashpot, which is slightly open while the valve is closed, closes and the valve piston starts downward, opening the valve. The head of the valve becomes exposed to the exhaust gas, but on only the upper side, while the area of the valve piston skirt exposed to the exhaust gas is decreased as the valve piston descends, this area being brought into contact with the cooling walls of the valve well. When the ordinary poppet exhaust valve is open, both sides of the valve head and a considerable portion of the valve stem are not only exposed to the exhaust gas, but are in the very center of the flow of the gas, the exposed area being more than double the exposed area in my valve. No part of my valve is in the direct path of the gas leaving the cylinder, and the gas leaves with a lower velocity, as it has a larger opening, with no obstructions in it, through which to pass.

The part of my valve which is exposed to the heat of the cylinder contents during the power stroke is being cooled during the exhaust stroke, while in the case of the ordinary poppet valve, it is not only not being cooled at any point except the valve stem, and very poorly there, but it is much more exposed to the heat of the exhaust gas. On the exhaust stroke, therefore, my valve will remain very much cooler. This is particularly so, also, because the head of my valve, having to withstand only the relatively low pressure of the exhaust gas, can be made very

70

much lighter than the head of an ordinary poppet valve which must withstand the relatively high explosion pressure. Consequently the heat will be carried away from the smaller mass of metal much more quickly.

The ordinary poppet valve cannot be cooled to any considerable extent by the incoming fuel mixture. On the contrary, it is very simple with my valve, to direct part of the fuel mixture entering through the intake valve, in such a way that it will flow around the exhaust valve piston, both cooling the valve and warming the fuel mixture.

When the engine is running at low speed, the dashpot remains closed and the valve piston and valve stem move as a unit, the pressure of the valve spring and the pressure of the air in the chamber at the bottom of the valve well being sufficient to overcome the momentum of the valve piston before the dashpot can open. The valve therefor opens a distance corresponding to the eccentricity of the cam. As the cam rotates farther, it forces the cam roller up and the valve closes, the dashpot opening slightly and the valve spring being compressed slightly more. At low speed, then, the valve is firmly seated and is firmly held in position in its seat.

When the valve is closed, the openings of the oil inlet passage and of the oil outlet passage are open. Oil from the oiling system enters the bottom of the valve well through the oil inlet passage. If the level of the oil in the valve well is below the opening of the oil outlet passage, no oil passes out and the incoming oil continues to raise the level of the oil. When the level of the oil reaches the opening of the oil outlet passage, enough oil passes out through that passage to keep the oil level at approximately the level of the oil passage openings.

As the valve opens and the valve piston descends, the openings of both oil passages are closed by the lower part of the valve piston skirt. The entrance of the lower part of the valve piston skirt and retaining ring into the oil, raises the oil level. At the same time the cupped washer is descending, so that the volume in the chamber available for the air is reduced and the pressure of the air is increased. This air pressure forces some of the oil up between the valve piston skirt and the bore of the valve well, lubricating the valve piston and piston rings and making a gas tight and air tight seal between the valve piston and the bore of the valve well. A little of the oil is forced out through the oil passages and a little through the bearing of the valve stem in the bottom of the valve well, but the total amount is small and the effect on the air pressure in the bottom of the valve well is negligible. The lubrication of the valve is very positive and thorough.

As the speed of the engine increases, the velocity of the valve piston increases and the

momentum of the valve piston increases as the square of its velocity. Above a certain engine speed, then, the momentum of the valve piston will overcome the pressure of the valve spring and the pressure of the air in the bottom of the valve well.

Consequently the distance which the valve piston descends will be greater than the distance the head of the valve stem descends, the valve will open wider and the dashpot will be opened. The higher the engine speed and the greater the momentum of the valve piston, the farther the latter will descend, although, as the valve piston descends farther, the space available for the air in the bottom of the valve well is further decreased and the air pressure increased, and the valve spring is further compressed. Hence, the increased momentum and increased movement of the valve piston is met by increased resistance.

The strength of the valve spring and the volume available for the air in the bottom of the valve well may be so adjusted that, at the maximum speed of the engine, the valve piston will descend to a certain maximum distance which will leave proper clearance between the various parts, so that the bottom of the valve piston skirt will not strike the bottom of the valve well and the bottom of the cupped washer will not strike the head of the valve stem.

The movement of the valve piston downward, due to its momentum, occupies a short space of time during which the cam will have passed the position where its lowest point is in contact with the cam roller, and the latter will have started upward by the time the valve piston has been brought to rest. The approximate positions occupied by the various parts at this instant are shown in Figure 1.

Since the pressure of the air in the bottom of the valve well increases as the valve piston descends farther, and as the inertia of the air is very small, the valve piston is given a very strong upward push by this pressure, so that it starts upward much more quickly than it would were its initial impulse to come only from a spring.

Consequently, while the valve piston travels farther in less time at high engine speeds, it does so without any pounding and without any unduly high pressure on any bearing.

The design of the cam is such that the valve stem gradually comes to rest, while the air pressure, valve spring pressure and the momentum of the valve piston cause it to move faster, near the end of the closing stroke, than the valve stem does. The groove in the retaining ring is filled with oil whenever the dashpot is open, and this oil is forced out of the groove by the ring on the valve stem head as the dashpot closes, bringing the valve piston to rest without shock, with the valve

head seated in the valve seat. But it takes an appreciable time for the oil to escape from the groove through the narrow clearance between the inner wall of the groove and the 5 ring on the valve stem head, as the dashpot closes, so that the valve closes a little later than it would if it were not for the action of the dashpot.

Thus, at high speed the valve opens farther, remains open a little longer, and closes gently, which are all conditions necessary for the best results in the operation of the engine. The closing of the valve is positive and uniform at any given speed, being controlled by the action of the cam and not by the action of a spring.

Provision has been made so that the valve may be adjusted. This is accomplished by means of the screw thread connection between the valve stem and push rod. The proper adjustment requires that the dashpot be slightly open when the valve is closed, so that unequal expansion of the parts of the engine, as it gets hot, will not interfere 25 with the functioning of the valve. As the cylinder lengthens, the valve seat moves upward. The expansion of the valve and actuating mechanism is not likely to exactly compensate this displacement.

30 By unscrewing the screw plug in the bottom of the valve well a gauge may be inserted to ascertain the position of the valve piston at any point of the valve cycle. By hanging a bent wire, for instance, on the inner edge of the retaining ring, so that the movement of the visible part of the wire will indicate the movement of the valve piston, the combined length of the push rod and valve stem can be adjusted so that the valve stem 40 will start downward slightly before the valve piston starts downward, as the valve opens, or so that the valve stem has a slight motion upward after the valve piston stops, as the valve closes. The valve is then in adjustment.

45 The lock nut setting the adjustment is tightened, the gauge removed and the plug screwed back into its seat in the bottom of the valve well.

50 Since the valve is thoroughly lubricated and since it stays cool and will need to be ground infrequently, it will require very little attention, upkeep, and adjustment.

55 The operation of the intake valve and its adjustment are similar to those of the exhaust valve. The intake valve cam is so formed as to cause the intake valve to open only after the exhaust valve has closed at its latest point, that is, when the engine is 60 being operated at its highest speed. The time of opening of the valves is not changed by the speed of the engine, while the time of closing the valves is changed. The head of the intake valve is exposed to the fuel mixture, but not to the exhaust gas, so that the

intake valve remains cooler than the exhaust valve.

I claim:

1. In an internal combustion engine, a valve comprising two main parts, said parts being connected together in such manner as to be capable of a motion relative to each other in the direction of the axis of said valve, and a dashpot, said motion being limited in one direction by said dashpot.

2. In an internal combustion engine, a valve comprising two main parts, said parts being connected together in such manner as to be capable of motion relative to each other in the direction of the axis of said valve, and a spring adapted to limit said motion in one direction and to cause said motion in the opposite direction.

3. In an internal combustion engine, a cylinder block, a cylinder formed in said cylinder block, a valve for said cylinder, and an air chamber formed in said cylinder block, with air in said chamber, the construction of said valve and said air chamber being such that the opening of said valve decreases the volume of said air chamber, increasing the air pressure opposing the motion of said valve, and the closing of said valve increases the volume of said air chamber, decreasing the air pressure assisting the motion of said valve.

4. In an internal combustion engine, a valve comprising two main parts, said parts being connected together in such manner as to be capable of a limited motion relative to each other in the direction of the axis of said valve, one of said parts comprising a circular head and a hollow cylindrical body, and the other of said parts comprising a valve stem with a cylindrical head, said cylindrical head being adapted to have a sliding fit within the cylindrical body of the first mentioned of said parts.

5. In an internal combustion engine, a valve comprising two main parts, said parts being connected together in such manner as to be capable of a limited motion with respect to each other in the direction of the axis of said valve, one of said parts comprising a circular head and a hollow cylindrical body, and the other of said parts comprising a valve stem with a cylindrical head, and a dashpot for limiting said relative motion and for transmitting motion from one of said parts to the other of said parts, said dashpot comprising an annular ring formed on said head of said valve stem, and an annular groove formed in a retaining ring, said retaining ring being positioned within said cylindrical body of the first mentioned of said parts, said groove being adapted to receive oil, and said ring adapted to enter said groove with a variable clearance between the side of said groove and said ring, all sub-

stantially as shown in the drawings and as described in the specification.

6. In an internal combustion engine, a valve comprising two main parts, said parts being connected together in such manner as to be capable of a limited motion relative to each other in the direction of the axis of said valve, one of said parts comprising a circular head and a hollow cylindrical body, and the other of said parts comprising a valve stem with a cylindrical head, and a dashpot for limiting said relative motion and for transmitting motion from one of said parts to the other of said parts, and a spring, said spring adapted to limit the relative motion of said parts and to transmit motion from one of said parts to the other of said parts, said spring being positioned within said cylindrical body of the first mentioned of said parts, all substantially as shown in the drawings and as described in the specification.

7. In an internal combustion engine, a cylinder block, a cylinder formed in said cylinder block, a cylindrical valve well formed in said cylinder block, and a valve for said cylinder, said valve comprising two main parts capable of a limited motion relative to each other in the direction of the axis of said valve, one of said parts comprising a circular head and a hollow cylindrical body, said cylindrical body being positioned in said cylindrical valve well, and the other of said parts comprising a valve stem with a cylindrical head, said valve stem being positioned in a bearing in the bottom of said valve well, the bottom of said valve well forming an air chamber, one of said parts of said valve closing said air chamber in such manner that the opening of said valve decreases the volume of said air chamber, increasing the air pressure opposing the motion of said valve, and the closing of said valve increases the volume of said air chamber, decreasing the air pressure assisting the motion of said valve, substantially as shown in the drawings and as described in the specification.

8. In an internal combustion engine, a lubricating system for a valve and valve actuating system, comprising an oil inlet passage to a valve well, said oil inlet passage adapted for connection to an oil supply system, an oil outlet passage from said valve well, said oil outlet passage connecting said valve well with a chamber containing part of said valve actuating mechanism, and an outlet from said chamber to another chamber containing another part of said valve actuating mechanism, the openings of said oil inlet passage and of said oil outlet passage into said valve well being adapted to be open when said valve is closed, and to be closed when said valve is open, substantially as shown in the drawings and as described in the specification.

9. In an internal combustion engine com-

prising a cylinder, a piston within said cylinder, and a passage in communication with said cylinder, the combination therewith of a valve for opening and closing said passage, means including a cam for positively carrying the valve to a point adjacent closed position after which the momentum of the valve causes it to fully close, means for cushioning the seating of the valve, and means including a spring for opening said passage.

10. In an internal combustion engine, valve mechanism including a positive acting cam and a cushioning device for closing the valve, and means including a spring for opening said valve.

11. In an internal combustion engine of the type including a cylinder, a piston within the cylinder and a passageway in communication with said cylinder, the combination therewith of a valve seat in said passage, a valve having a head to cooperate with said valve seat for opening and closing said passage, said valve having a stem portion of slightly less diameter than the valve head and forming an annular surface parallel to the plane of the valve seat upon which the combustion gases may exert a pressure for maintaining said valve in a closed position during the power stroke of the engine, positive means for closing said valve and resilient means for opening it.

12. A valve mechanism for internal combustion engines comprising in combination a valve piston, a valve stem, means for actuating said valve stem, and resilient means for making a driving connection between said valve piston and said valve stem.

13. A valve mechanism for internal combustion engines comprising in combination a valve seat, a valve piston, a valve stem, means for actuating said valve stem, means for driving said valve piston by said valve stem, and means for cushioning the seating of the valve in the valve seat.

14. A valve mechanism for internal combustion engines comprising in combination a valve seat, and a valve cooperating with said valve seat, means for positively moving said valve into its seated position, spring means for moving said valve from its seated position, and means for cushioning the seating of the valve.

15. A valve mechanism for internal combustion engines comprising in combination a valve seat, a valve piston adapted to cooperate with said seat to close a passageway, a valve stem, means for actuating said valve stem in synchronism with the motor, and means including a spring positioned between the valve piston and the valve stem for automatically attaining a wider opening of the valve at high motor speeds.

16. A valve mechanism for internal combustion engines comprising in combination a valve seat, a valve piston adapted to cooper-

ate with said valve seat for closing a passageway, a valve stem, means for actuating said valve stem in synchronism with the motor, a spring positioned between the valve piston and the valve stem for urging said valve piston into seated position, and means including a dash pot arrangement for unseating the valve.

17. A valve mechanism for internal combustion engines comprising in combination a valve seat, a valve for cooperating with said seat to close a passageway, said valve including a valve head and a valve stem, means for actuating said valve stem, and means intermediate said valve head and valve stem for cushioning the seating of the valve.

18. An internal combustion engine comprising in combination a cylinder, a piston within the cylinder, and a passage in communication with said cylinder, a valve seat in said passage, a valve having a head shaped to cooperate with said valve seat, said valve having a stem, said valve being arranged with respect to said cylinder so as to expose a portion of the valve stem to the gaseous mixture within the cylinder when the valve is in seated position, the exposed portion of said valve stem being of such diameter relative to the valve head so as to provide a relatively small area upon which the products of combustion may act to resist the opening of the valve, positive means for closing said valve and resilient means for opening it.

19. A valve mechanism for internal combustion engines comprising in combination a valve seat, a valve piston adapted to cooperate with said seat to close a passageway, a valve stem, means for actuating said valve stem in synchronism with the motor, means including a spring positioned between the valve piston and the valve stem for automatically attaining a wider opening of the valve at high motor speeds, and means including a closed air chamber for increasingly cushioning the downward movement of the valve and for assisting the spring for starting the valve on its upward stroke at the said higher speeds of the motor.

20. In an internal combustion engine comprising a valve well, the combination therewith of a valve piston adapted to reciprocate therein and having an elongated skirt portion, a valve stem extending upwardly within the said skirt portion, a spring positioned within the piston and forming a driving connection between the valve stem and the valve piston, said valve stem having an annular depending rim for cooperating with an interior annular groove carried by said skirt portion for forming a dash pot, and a plug closing the interior of said valve piston against the admittance of air.

21. An internal combustion engine comprising in combination a cylinder block, a valve well within the block, a valve piston

adapted to reciprocate therein and having an elongated skirt portion, means for actuating said valve piston including a valve stem, extending within said piston and having a driving connection therewith, means for lubricating said piston including a lubricating port adapted to admit a lubricant when the valve is in seated position but not being in communication with the interior of the piston when the valve is in unseated or open position.

22. In an internal combustion engine comprising a valve well, the combination therewith of a valve piston adapted to reciprocate therein and having an elongated skirt portion, a valve stem extending upwardly within the said skirt portion, a spring positioned within the piston and forming a driving connection between the valve stem and the valve piston, said valve stem having an annular depending rim for cooperating with an interior annular groove carried by said skirt portion for forming a dash pot, a plug closing the interior of said valve piston against the admittance of air, and means for lubricating said valve including a lubricating port adapted to communicate with the interior of the valve piston when the valve is in closed position.

23. In an internal combustion engine comprising a valve well, the combination therewith of a valve piston adapted to reciprocate therein and having an elongated skirt portion, a valve stem extending upwardly within the said skirt portion, a spring positioned within the piston and forming a driving connection between the valve stem and the valve piston, said valve stem having an annular depending rim for cooperating with an interior annular groove carried by said skirt portion for forming a dash pot, a plug closing the interior of said valve piston against the admittance of air, and means for admitting oil for forming an air seal between said piston and the valve well.

24. In an internal combustion engine comprising a valve well, the combination therewith of a valve piston adapted to reciprocate therein and having an elongated skirt portion, a valve stem extending upwardly within the said skirt portion, a spring positioned within the piston and forming a driving connection between the valve stem and the valve piston, a cup-shaped member arranged to form an air chamber in the upper portion of said piston, means for relieving the pressure in said air chamber, said valve stem having an annular depending rim for cooperating with an interior annular groove carried by said skirt portion for forming a dash pot, and a plug closing the interior of said valve piston against the admittance of air.

25. An internal combustion engine comprising in combination a valve well, a valve

piston within the well, a valve stem extending upwardly through the base of the valve well into the said piston, said valve stem having a driving connection including a spring with said valve piston, a closed air chamber formed between the base of the valve well and the valve piston, and means for creating a pressure within said chamber for assisting the action of the spring in driving said piston.

26. A valve mechanism for internal combustion engines comprising in combination a valve head and a valve stem, means for actuating said valve stem in synchronism with the motor, a spring positioned between the valve head and the valve stem for urging said valve into a closed position upon a given movement of the stem and for cushioning the movement of the head when the stem is moved in the opposite direction.

27. In an internal combustion engine of the type including a cylinder block, a cylinder within the block, a piston adapted to reciprocate within the cylinder, a cylinder head having a passage communicating with the cylinder, a valve seat in the head, a valve well in the block in axial alignment with the valve seat, a valve in the well adapted to open and close said passageway, positive means for moving the valve to seated position and resilient means for withdrawing the valve, said valve being arranged to provide a clear and unobstructed passageway when said valve is in open position.
